UNITED STATES PATENT OFFICE

CHARLES F. OSGOOD, OF CLAREMONT, NEW HAMPSHIRE, ASSIGNOR TO SULLIVAN MACHINERY COMPANY, A CORPORATION OF MASSACHUSETTS

DRILLING MECHANISM

Application filed March 8, 1924, Serial No. 697,941. Renewed April 18, 1931.

My invention relates to drilling mechanism.

It has for its object to provide an improved drilling mechanism and more particularly an improved drilling mechanism especially adapted to use in deep well work such as in drilling for oil or gas. A further object of my invention is to provide improved means for guiding the drill line, the same herein being also especially adapted for use with mud fluid and for cooperation with a core barrel. These and other objects of my invention will hereinafter more fully appear.

In the accompanying drawing I have shown for purposes of illustration several forms which my invention may assume in practice.

In the drawing,—

Fig. 1 is a side elevation partially in longitudinal section showing one form of my improvement.

Fig. 2 is a transverse sectional view on line 2—2 of Fig. 1.

Fig. 3 is a transverse sectional view on line 3—3 of Fig. 1.

Fig. 4 is a side elevation of a modified form of construction.

Fig. 5 is a similar view of a further modified form.

In the illustrative construction, shown in Figs. 1 to 3, I have shown a drill rod line 1 having an external coupling 2 threaded on the reduced inner end of the innermost rod section and likewise threaded on the reduced outer end of a suitable core barrel 3. This member 2 is herein also provided with a series of longitudinal flutes 4 cooperating to form wings 5, of the same or substantially the same external diameter as the core barrel bit hereinafter mentioned, and thus form a combined coupling and guide having passages therethrough for the passage of mud fluid. It will also be noted that as usual in a well known type of core drill, the core barrel

3 carries at its lower end a bit 6 of the winged type having wings 7 formed by suitable straight longitudinally disposed flutes 8 between the same, the flutes being of substantially the same area as the flutes in the member 2, while other mud fluid passages 9 are

provided in the inner periphery of the bit. As in a usual construction, the bit 6 is also threaded to the lower end of the core barrel and the latter carries therein a suitable core lifter 10. Thus, considering the members 2 and 6, it will be noted that these members cooperate to provide guiding and mud fluid passage means at opposite ends of the core barrel and thus create a construction which keeps the core barrel in the desired rectilinear path at the same time that it permits the mud fluid, which in practice is passed down through the rod line, the core barrel 3 and passages 9 in the bit, to pass freely upward along the outside of the rod line, the flutes 8 in the bit and flutes 4 in the coupling permitting free movement thereof.

In Fig. 4 I have illustrated a modified construction in which it will be noted that a second coupling 2 is disposed between the ends of the core barrel 3, the latter in this construction being capable of being made in two parts 11 and 12 if desired, although the member 2 may obviously be suitably fixed to the exterior of a single piece core barrel tube in any suitable manner if desired, the coupling function then of course being eliminated. In this construction it will be observed that the extra member 2 serves as an extra guiding member supplementing the bit 6, and the guiding member 2 connecting the core barrel to the rod line. In Fig. 5 I have shown a further modified construction in which while a member 2 is disposed between the outer end of the core barrel and the rod line, one or more sections of the rod line are connected by extra members 2 thereby insuring further guiding of the rod line and core barrel while still permitting the desired flow of mud fluid and further preventing whipping of the rod line in the hole. Obviously if desired any desired number of sections of the rod line may be connected by such improved members 2.

As a result of my improved construction it will be noted that all necessity for providing an elongated grooved section on the core barrel, or of grooving the entire length of the barrel as has heretofore been done in certain instances, is eliminated, the member 2 coop-

erating in the form shown in Fig. 1 with a bit to make an intermediate guiding portion unnecessary and thereby materially reducing the cost of the barrel at the same time that the desired guiding and mud fluid flow is maintained. Obviously the form shown in Fig. 4 while more expensive than that shown in Fig. 1 will still reduce the expense heretofore involved while producing the desired result. As for the form shown in Fig. 5, the results obtainable by the construction shown in Fig. 1 will be obtained with the additional result that whipping of the rod line will be prevented. These and other advantages of my invention will, however, be clearly apparent to those skilled in the art.

While I have in this application specifically described several forms which my invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a drilling mechanism, a rod line, a tubular core barrel, an annular winged core cutting bit detachably connected to the inner end of said barrel, and a detachable coupling member connected to and rotatable with said barrel for detachably connecting the outer end of said barrel to said rod line, said coupling member being of a diameter substantially larger than said rod line and core barrel and having externally enlarged guiding wings substantially fitting the drill hole cut by the bit and slidably engaging, with a purely guiding function, the walls of the drill hole as the drill is fed inwardly, said coupling member and bit having fluid passages between the wings thereon.

2. In a drilling mechanism, a sectional rod line, a tubular core barrel, an annular winged core cutting bit detachably connected to the inner end of said barrel, and a plurality of longitudinally spaced detachable coupling members carried on and rotatable with the rod line and disposed above said bit, said coupling members detachably connecting the rod line sections and each being of a diameter substantially larger than the rod line and core barrel and having externally enlarged guiding wings substantially fitting the drill hole cut by the bit and slidably engaging, with a purely guiding function, the walls of the drill hole as the drill is fed inwardly, said coupling members and bit having fluid passages between the wings thereon.

3. In a drilling mechanism, a rod line, a tubular core barrel, an annular winged core cutting bit detachably connected to the inner end of said barrel, a detachable coupling member connected to and rotatable with said

barrel for detachably connecting the outer end of said barrel to said rod line, said coupling member being of a diameter substantially larger than said rod line and barrel and having externally enlarged guiding wings substantially fitting the drill hole cut by the bit and slidably engaging, with a purely guiding function, the walls of the drill hole as the drill is fed inwardly, and a supplemental winged member spaced longitudinally from said winged coupling member, said members and said bit having fluid passages between the wings thereon.

4. In a drilling mechanism, a rod line, a tubular core barrel, an annular winged core cutting bit detachably connected to the inner end of said barrel, a detachable coupling member connected to and rotatable with the barrel for detachably connecting the outer end of said core barrel to the rod line, said coupling member being of a diameter substantially larger than said rod line and core barrel and having externally enlarged guiding wings substantially fitting the drill hole cut by the bit and slidably engaging, with a purely guiding function, the walls of the drill hole as the drill is fed inwardly, and a supplemental externally enlarged winged guiding member spaced longitudinally from said winged coupling member and carried by and rotatable with the rod line, said members and said bit having fluid passages between the wings thereon.

5. In a drilling mechanism, a rod line, a tubular core barrel, an annular winged core cutting bit detachably connected to the inner end of said barrel, and a detachable coupling member connected to and rotatable with said barrel for detachably connecting the outer end of said barrel to the rod line, said coupling member being of a diameter substantially larger than said rod line and barrel and having externally enlarged straight longitudinally extending wings substantially fitting the drill hole cut by the bit and slidably engaging, with a purely guiding function, the walls of the drill hole as the drill is fed inwardly, and fluid passages between the wings on said coupling members and said bit.

6. In a drilling mechanism, a sectional rod line, a tubular core barrel detachably connected to said rod line, an annular core cutting bit detachably connected to the inner end of said barrel, and externally enlarged detachable coupling members connected to and rotatable with the rod line for detachably connecting the sections of said rod line and said barrel to said rod line, said coupling members being of a diameter substantially larger than said rod line and barrel and having guiding wings formed externally thereon and substantially fitting the drill hole cut by the bit and slidably engaging, with a purely guiding function, the walls of the drill hole as the drill is fed inwardly,

- and fluid passages between the wings on said members. 70
7. In a core drill, a rod line, a tubular core barrel and an annular core cutting bit detachably secured thereto at its inner end, and a combined detachable coupling and guide member connected to and rotatable with said barrel for detachably connecting the outer end of said barrel to the rod line, 75 said coupling and guide member being of a diameter substantially larger than said rod line and barrel and substantially fitting the drill hole cut by the bit and slidably engaging, with a purely guiding function, the walls of the drill hole as the drill is fed inwardly, 80 said coupling and guide member having externally enlarged guiding wings and fluid passages between the wings. 85
8. In a drilling mechanism, a sectional rod line, a core barrel detachably connected thereto, an annular core cutting bit detachably connected to said barrel, and externally enlarged detachable coupling members connected to and rotatable with the rod line for detachably connecting the sections of said rod line together and said barrel to said rod line, said coupling members being of a diameter substantially larger than the rod line and barrel and having straight longitudinally 90 extending guiding wings formed externally thereon and substantially fitting the drill hole cut by the bit and slidably engaging, with a purely guiding function, the walls of the drill hole as the drill is fed inwardly, 95 and fluid passages between the wings on said coupling members. 100
9. In a core drill, a rod line, a core barrel attached to the inner end of the rod line, an annular core cutting bit attached to the inner 105 end of the core barrel, and guiding means for the rod line and core barrel comprising guide members attached to the rod line at spaced points along its length, said guide members being of a diameter substantially larger than the rod line and barrel and substantially fitting the drill hole cut by the bit and slidably engaging, with a purely guiding function, the walls of the drill hole as the drill is fed inwardly, 110 said guide members having externally enlarged guiding wings and fluid passages between the wings thereon. 115
10. In a core drill, a rod line, a tubular core barrel detachably connected to the inner end of said rod line, an annular core cutting bit detachably connected to the inner end of said core barrel, and means for guiding the rod line and core barrel in the drill hole comprising guide members attached to the rod line and core barrel and spaced longitudinally of the drill string, said guide members being detachably connected to the rod line and barrel and of a diameter substantially larger than the rod line and barrel and having guiding wings formed externally 120 thereon and substantially fitting the drill 125
